UNITED STATES PATENT OFFICE.

DAVID F. TABER, OF NEW YORK, N. Y.

STEAM-BOILER-TUBE CLEANER.

No. 839,523.

Specification of Letters Patent.

Patented Dec. 25, 1906.

Application filed May 28, 1906. Serial No. 319,050.

To all whom it may concern:

Be it known that I, DAVID F. TABER, a citizen of the United States, residing in the city of New York, borough of Brooklyn, county 5 of Kings, and State of New York, have invented certain new and useful Improvements in Steam-Boiler-Tube Cleaners, which the following is a specification.

My invention relates to what are known as 10 "blowers" for injecting steam into and through boiler-tubes for the purpose of dislodging and removing soot and other solid products of combustion from said tubes, and particularly to the class of such blowers de- 15 signed for use at the rear of return tubular boilers, the blowers in such cases being installed in the rear wall of the combustion-chamber. As heretofore constructed these blowers can only be applied to the back walls 20 of boiler-furnaces which are accessible from the rear and have to be operated manually.

My invention is designed to afford a comparatively simple and inexpensive blower which will be automatic in action and which 25 may be applied to the rear wall of any boiler-furnace, even though there is no available space behind said rear wall, as where the latter abuts against a wall, partition, or obstruction of any kind.

30 In the accompanying drawings, Figure 1 is a vertical section of the rear portion of a return-tube boiler and furnace to which my blower is applied. Fig. 2 is a sectional elevation of the rear wall of the furnace, taken 35 upon the plane of line 2 2, Fig. 1. Fig. 3 is a vertical longitudinal section of the casing. Fig. 4 is a side elevation of the rotatable nozzle. Fig. 5 is a vertical section upon plane of line 5 5, Fig. 7. Fig. 6 is an end elevation of 40 the nozzle and casing. Fig. 7 is a section of the nozzle and casing on plane of line 7 7, Fig. 6, the nozzle being in its normal or retracted position. Fig. 8 is a similar view 45 showing the rotatable nozzle protruding from the casing. Fig. 9 is an enlarged sectional view of the inner end of the nozzle and casing.

A represents the rear end of a return-flue boiler of any desired type or construction, 50 and B the rear wall of the furnace inclosing the end of the boiler and the rear extension of the combustion-chamber C.

55 Embedded in the wall B with its longitudinal axis preferably coincident or nearly coincident with the center of the area occupied by the tubes to be cleaned is the casing

D, consisting of a cylindrical shell having a port d at the rear, said port communicating through a pipe or conduit d' with a steam-pressure pipe e, provided with the valve e'. 60 The pipe d', supplying steam through the port d to the shell D, is preferably inclined downward, as shown by way of illustration in Fig. 2, and has interposed between it and the steam-pressure pipe e a drip-chamber e², provided with a petcock e³, so that when the valve e' is closed after the blower has been in use the drip or water of condensation may be drawn from both pipes.

The recess b in the wall B, in which the shell D is embedded, is preferably longer than the shell by approximately the extent or protrusion of the nozzle N, so that the head n of the nozzle will be substantially flush with the inner surface of the wall when the nozzle is in 75 use. This is to protect the nozzle as far as possible from direct contact with the products of combustion in the chamber C.

The nozzle N consists of a hollow cylinder the main portion of which is of less diameter 80 than the internal diameter of the shell D, but which has at or near its inner extremity an annular shoulder n' of essentially the same diameter as the interior of the shell D, so as to fit snugly therein.

Formed integral with or rigidly secured to the shell D is an internal annular shoulder d', between which and the annular shoulder n' on the nozzle N is interposed a coiled spring S, which tends constantly to hold the nozzle 90 N retracted within the shell D. This retractile movement is limited by another annular shoulder n² on the front end of the nozzle N, which rests normally against the internal annular shoulder d' on the shell D. 95

The outer or face end of the nozzle is closed by a relatively thick head n, through which extend a series of steam-passages n³, all but the central one of which converge inwardly toward the longitudinal axis of the nozzle, so 100 as to deflect the steam escaping from the nozzle N over a relatively wide area and inject the steam into the various tubes a of the boiler A, the said passages n³ n³ in the nozzle-head n being in sufficient number and arranged to meet the requirements of the class and size of boiler to which the blower is to be applied.

Cast or otherwise formed integral with the nozzle N is a spiral blade (one or more) n⁴, 105 inclined with relation to the longitudinal axis of the nozzle in such manner that the flow of

steam through the latter will cause it to rotate within the shell D.

While I do not limit myself to any special method of construction, the nozzle N may be cast in one piece with the curved blade n^4 and head n , the steam-passages n^3 n^3 being cored in the latter. In such case the annular shoulders d^2 and n^2 are secured in position after the spring S has been applied peripherally to the nozzle N. In this connection it may be noted that while the shoulders n^2 , d^2 , and n^2 are preferably of continuous annular form still this structure is not indispensable, since the main function of the stops d^2 and n^2 is to act as bearings for the ends of the spring S, while that of the shoulder n^2 is to act as a stop or rest for the parts when in their normal positions at rest.

In use when it is desired to blow out and clean the boiler-tubes a the valve e' in the supply-pipe e is opened, thereby admitting steam under pressure to the casing D. at the rear of the nozzle N. As a result the nozzle N is forced forward against the resistance of the spring S, and at the same time the nozzle is rotated on its longitudinal axis by reason of the pressure and flow of the steam on and over the spiral surface of the blade n^4 . By this rotation of the nozzle N the steam-passages n^3 n^3 are made to inject the steam successively into all the boiler-tubes, and it will be noted that this operation will be continuous and automatic as long as the steam-pressure is maintained. When the valve e' is closed, the spring S returns the nozzle N to its normal position out of contact with the products of combustion in the chamber C. Thus installed in position in the rear wall of the furnace my blower requires no further attention, and there being no protrusion of the parts at the rear of the furnace-wall it can be applied and used in situations where access cannot be had to the rear of the furnace-wall. Furthermore, the device is simple, cheap, and durable in structure and not liable to deteriorate or get out of order, as it is isolated and protected and subject only to the wear involved in actual use, which is limited to the automatic rotation of the nozzle.

50. What I claim as my invention, and desire to secure by Letters Patent, is—

1. In a device of the character designated, the combination with an inclosing shell and with means for supplying steam under pressure thereto, of a longitudinally - movable nozzle formed with a spiral surface arranged to automatically effect the axial rotation of the nozzle by the flow of steam through the nozzle, the latter being also formed with one or more steam-passages in its discharge-head inclined with relation to the longitudinal axis

of the nozzle, and a spring arranged to hold the nozzle in its normal position within the shell when not in use, for the purpose described.

2. In a device of the character designated, the combination with an inclosing shell and with means for supplying steam under pressure thereto, of a longitudinally - movable nozzle formed with a spiral surface arranged to automatically effect the axial rotation of the nozzle by the flow of steam through the nozzle, the latter being also formed with one or more steam-passages in its discharge-head inclined with relation to the longitudinal axis of the nozzle, and a spring surrounding the nozzle and interposed between it and the inclosing shell, one end of said spring resting against a shoulder on the nozzle and the other against a shoulder on the shell for the purpose described.

3. In a device of the character designated, the combination with a return-flue boiler and furnace, of a nozzle-inclosing shell embedded in the rear wall of the boiler-furnace in a recess opening into the combustion-chamber, means for supplying steam under pressure to said inclosing shell, a longitudinally-movable nozzle in said shell formed with a spiral surface arranged to automatically effect the axial rotation of the nozzle by the flow of steam through the nozzle, the latter being also formed with one or more steam-passages in its discharge-head inclined with relation to the longitudinal axis of the nozzle, and a spring arranged to hold the nozzle in its normal position within the shell when not in use, for the purpose described.

4. In a device of the character designated, the combination with a return-flue boiler and furnace, of a nozzle-inclosing shell embedded in the rear wall of the boiler-furnace in a recess opening into the combustion-chamber, means for supplying steam under pressure to said inclosing shell, a longitudinally-movable nozzle in said shell formed with a spiral surface arranged to automatically effect the axial rotation of the nozzle by the flow of steam through the nozzle, the latter being also formed with one or more steam-passages in its discharge-head inclined with relation to the longitudinal axis of the nozzle, and a spring surrounding the nozzle and interposed between it and the inclosing shell, one end of said spring resting against a shoulder on the nozzle and the other against a shoulder in the shell, for the purpose described.
